US0D1071989S

(12) **United States Design Patent** (10) Patent No.: **US D1,071,989 S**
Gerrese et al. (45) Date of Patent: ** Apr. 22, 2025

(54) **DISPLAY SCREEN OR PORTION THEREOF WITH A GRAPHICAL USER INTERFACE**

(71) Applicant: **GM Cruise Holdings LLC**, San Francisco, CA (US)

(72) Inventors: **Alexander Gerrese**, San Francisco, CA (US); **Kendal Sparks**, New York, NY (US); **Brian Wong**, San Francisco, CA (US)

(73) Assignee: **GM Cruise Holdings LLC**, San Francisco, CA (US)

(**) Term: **15 Years**

(21) Appl. No.: **29/879,774**

(22) Filed: **Jul. 12, 2023**

(51) LOC (15) Cl. **14-04**
(52) U.S. Cl. ..... **USPC D14/492; D14/490**
